JACOB J. STARK
BY *M. M. Stark*
ATTORNEYS

UNITED STATES PATENT OFFICE.

JACOB J. STARK, OF BROOKLYN, NEW YORK.

DENTAL BRIDGEWORK.

Application filed December 7, 1922. Serial No. 605,475.

To all whom it may concern:

Be it known that I, JACOB J. STARK, a citizen of the United States, and a resident of the city of New York, borough of Brooklyn, in the county of Kings and State of New York, have invented certain new and useful Improvements in Dental Bridgework, of which the following is a full, clear, and exact description.

10 This invention relates to dental bridge work, and more particularly aims to provide a new and improved means for removably mounting one or more artificial teeth between two natural teeth in the mouth.

15 The invention as preferably applied is used for intradental work, that is, the natural teeth in the gums form the anchorages for the female members, in any suitable way, as by means well known in the art.

20 It is a fact well appreciated that much difficulty has been experienced with such mountings as previously proposed, and especially those mountings in which the female members on the natural teeth and the 25 male members carried by the removable bridge are both of T-shape, as is desirable, and with the head of the male member comprised of two substantially V-shaped head-valves on opposite sides of the shank, each

30 such half constructed of a unitary length of spring metal integral with the shank. Such a head as so constructed frequently requires manual adjustment of the opposite legs of the V, to increase or decrease the resilient 35 pressure of these parts relative to the appropriate female mounting on the bridge. Repeated adjustments of this kind quickly fatigue the localized line of bend at the apex of the V, the head loses its required resiliency, and often a leg of the V will break off.

An important object of the invention is to overcome this difficulty, as the result of making the head of the male member of such shape as to provide a multiplicity of bending points or lines; in other words, to make the head readily resiliently distortable and solely as the result of mounting the bridge in the mouth.

Another difficulty experienced with previous mountings of the above indicated character has been that if the spring-action of the head of a male member is set so that the bridge may be arranged in the mouth to avoid looseness detrimental to proper mastication and without danger of loosening the bridge accidentally, the bridge is rigidly

anchored; and then the bridge is exceedingly uncomfortable, and it is incapable of a limited movement relative to the natural teeth similar to that which nature provides for each natural tooth relative to another.

A further object of the invention is to overcome this latter difficulty, also, while avoiding the necessity for a pivotal or loose connection between the shank of a male member and the anchoring natural tooth; which, it is obvious, is not desirable, although such pivotal or loose connection is favored to a large extent at present as being a lesser evil than a bridge incapable of any relative movement whatever.

According to the present invention, and as preferably carried out pursuant to the structure shown in the accompanying drawing, or an equivalent, this last-mentioned object is attained automatically by the provision of such structure to attain the first object mentioned.

With these and various other objects in view, the invention consists in certain novel features of construction, and combinations and arrangements of parts, as will be hereinafter described and pointed out in the claim.

In the accompanying drawing, which shows by way of example, a possible structure according to the invention as at present preferred, and in which similar reference characters refer to similar parts throughout the several views:

Fig. 1 is a horizontal section, showing male and female member joined, and taken on the line 1—1 of Fig. 2.

Fig. 2 is a vertical section, taken on line 2—2 of Fig. 1;

Fig. 3 is a perspective view of the male member; and

Fig. 4 is a similar view of the female member.

The parts are shown on a greatly enlarged scale in the drawing.

As shown best in Figs. 3 and 4, male or stud member 5 conforms to the conventional construction in so far as the same is T-shaped in plan, is formed of an integral strip of material as illustrated, which material is preferably a spring metal, and has its T-head formed of two halves, each including two reversely bent portions; and female or socket member 6 also conforms to conventional construction in that the same has a tubular wall 7, a bottom 8 to establish a

general cup form, a cross-sectional area to receive snugly the head of the male member, and a slot 9 to take the root of the shank 10 of the male member when the parts are 5 assembled by sliding the head 11 of the male member down into the interior of member 6.

The constitution and construction of each half of head 11 of member 5 are of the essence of the present invention; although 10 a notch 12 cut in the root of shank 10 of the member 5, combined with the fact that the slot 9 of member 6 does not reach quite to the bottom of its cup, thereby to permit the parts to be arranged with approximately 15 level top and bottom surfaces as shown in Fig. 2, is a valuable feature of the new mounting.

Thus, it will be noted that member 5, in addition to the shank 10, includes a **T**-head, 20 each arm of which includes a strip of spring metal bent to form a spring bow, the concavities of said bows facing each other and the free ends of the **T**-arms being substantially in line with the 25 shank. Also, each such bow, at its free end adjacent to the free end of the other bow, carries rounded portions 14 adapted to slide on each other when the bows are compressed toward the shank. These rounded portions 30 are here inwardly directed cylindrical projections, which may conveniently be formed, as illustrated, by winding the transverse marginal lengths of the bows around pins or studs 15, soldered, welded, or otherwise 35 secured in place.

It will thus be seen that the new male member structure includes a shank and integral resilient continuations oppositely directed away from the shank and then inwardly directed toward the same to form a plurality of **T**-head portions each bendable at a multiplicity of points while resiliently resisting such bending. Otherwise stated, each half of the **T**-head, being a bow, is 40 bendable transversely along lines in a plurality of planes perpendicular to the plane of extension of the shank. Thus, each bowed spring element at the **T**-head of the male member is warpable simultaneously at 45 50 a plurality of points along the line of curva-

ture of the bow. It has also been found that the head of the male member when thus directed has portions resiliently relatively movable to adapt the head for distortion both laterally of the shank, toward and away from the shank, and also rockable relative to the shank on an axis parallel to the line of extension of the shank. The invention may be summed up in one word, as to its most salient characteristic, by pointing out that each half of the **T**-head of the male member is substantially **U**-shaped in plan and transversely resilient practically throughout its length, whereas the prior art device above discussed has a **T**-head 55 each half of which is **V**-shaped in plan, and limited to a localized line of bend at the apex of the **V**, for varying the resilient tendency of the **T**-head to increase its lateral dimensions; and, moreover, such 60 variation is not automatically responsive to the main mounting of the bridge in the mouth, but must preliminarily be manually 65 performed.

I would state in conclusion that while the 75 illustrated example constitutes a practical embodiment of my invention, the same, as above indicated, is merely an example of one of the multitude of ways in which the same may be carried out; and I do not 80 limit myself strictly to the exact details herein illustrated, since, manifestly, the construction may be considerably varied without departure from the spirit of the invention as defined in the appended claim. 85

I claim:

In a device of the class described, a stud structure **T**-shaped in plan, said structure including a shank forming the **T**-stem and including a pair of resilient strip elements 90 arranged side by side integral continuations of said elements being oppositely directed away from the stem and then inwardly directed toward the stem to form a plurality of **T**-head portions each bendable 95 at a multiplicity of points to vary the shape of the stem while resiliently resisting such bending.

JACOB J. STARK.
